[57] CLAIM

The ornamental design for a hanger bracket for attaching a fixture to a ceiling hanger assembly, as shown and described.

DESCRIPTION

FIG. 1 is a top perspective view of a hanger bracket for attaching a fixture to ceiling hanger assembly embodying my new design;

FIG. 2 is a bottom perspective view thereof;

FIG. 3 is a top plan view thereof;

FIG. 4 is a bottom plan view thereof;

FIG. 5 is a side elevational view of FIG. 1;

FIG. 6 is an end elevational view of FIG. 1; and

FIG. 7 is a top plan view thereof, it being understood that the broken lines are for illustrative purposes only and form no part of the claimed design.

FIG. 1

FIG. 2

FIG. 3

FIG. 4

FIG. 5

FIG. 6

FIG. 7
